UNITED STATES PATENT OFFICE.

WILLIAM F. FOSTER, OF NEW YORK, N. Y.

DESIGN FOR A LACING-HOOK FOR GLOVES.

SPECIFICATION forming part of Design No. 13,846, dated April 10, 1883.

Application filed September 6, 1882. Term of patent 14 years.

To all whom it may concern:

Be it known that I, WILLIAM F. FOSTER, residing in the city of New York, in the county and State of New York, have invented a new and original Design for Lacing-Hooks for Gloves, of which the following is a specification.

Figure 1 is an isometric view of my lacing-hook. Fig. 2 is a side view.

My hook has two prongs, *a*, at one end, from the top of which it curves upward to *b* and downward to *c*. It is then curved upward again and backward to the point of the hook at *d*. The hook proper is thus between the points *c* and *d*, and the portion of the device between *c* and *a* constitutes a projection, which rises above the material of the glove in front of the hook. When the hook is applied to the glove, it rests upon the material of the glove at the points *a* and *c*, and in this position the hook will rise considerably higher than the projection above the level of the glove material, while a direct passage exists between the hook and the projection *b*. These hooks may be plated or otherwise ornamented. For the purpose of ornamenting or distinguishing the

books I cause the impression of some device to be stamped into the substance forming the projection in front of the hook or into the substance forming the top of the hook itself. In the drawings I have represented the letter *F* upon the projection.

I claim—

1. The design for a lacing-hook herein shown and described, the same consisting of a hook proper, in combination with a projection situated in front of the hook, the projection rising above the material of the glove to a less height than the hook.

2. A lacing-hook so designed that, commencing at one end, the material composing it bends first upward above the level of the glove, then downward to the level of the glove, and then upward again, and so as to form the hook.

3. A lacing-hook having a projection raised above the glove in front of the hook, and being stamped with an ornamental or distinguishing mark, substantially as described.

WILLIAM F. FOSTER.
